UNITED STATES PATENT OFFICE

93,947

DESIGN FOR A TEXTILE FABRIC

Charles F. Scholle, Mount Vernon, N. Y., assignor
to Pepperell Manufacturing Company, Boston,
Mass., a corporation of Massachusetts

Application July 2, 1934, Serial No. 52,432

Term of patent 7 years

To all whom it may concern:

Be it known that I, CHARLES F. SCHOLLE, a citizen of the United States of America, residing at Mt. Vernon, in the county of Westchester, State of N. Y., have invented a new, original, and ornamental Design for Textile Fabric, of which the following is a specification, reference being had to the accompanying drawing, forming part thereof, in which the figure is a plan view of a textile fabric showing my new design.

The design unit shown by the drawing is repeated over the entire surface of the textile fabric.

I claim:

The ornamental design for a textile fabric as shown and described.

In testimony whereof I subscribe my signature.

CHARLES F. SCHOLLE.
